(57) **CLAIM**

The ornamental design for an elliptical snap handle assembly, as shown and described.

DESCRIPTION

FIG. 1 is a perspective view of an elliptical snap handle assembly showing my new design;

FIG. 2 is a front view thereof;

FIG. 3 is a rear view thereof;

FIG. 4 is a bottom view thereof;

FIG. 5 is a top view thereof; and,

FIG. 6 is an end view thereof, the opposite end view being substantially identical.
